Des. 198,418
Patented June 9, 1964

198,418

WRITING INSTRUMENT

Hans Reinhard Fehling, Zug, Switzerland, and Alfred Dennis Street, Pinner, England, assignors to I.R.C. Limited, London, England, a company of Great Britain

Filed Aug. 30, 1961, Ser. No. 66,549

Term of patent 14 years

(Cl. D74—17)

FIG. 1

FIG. 4

FIG. 2

FIG. 3

FIG. 1 is a top view of a writing instrument embodying the present design;

FIG. 2 is a side view of the writing instrument;

FIG. 3 is a bottom view of the writing instrument; and

FIG. 4 is an enlarged perspective fragmentary view illustrating the forward end of the writing instrument.

The dominant features of the design reside in the positioning on the writing instrument disclosed of an ink cartridge which emerges from an opening near the forward end thereof and lies in a groove that extends a short distance along the top surface of the forward end to the forward extremity of the holder from which the writing tip of the cartridge projects in a downward direction, all as shown.

We claim:

The ornamental design for a writing instrument as shown and described.
